Filed July 13, 1965, Ser. No. 471,595

7 Claims. (Cl. 206—65)

ABSTRACT OF THE DISCLOSURE

This invention is directed to a wrapper type can carrier formed of a foldable blank of sheet material comprising a top panel, a bottom panel, and a pair of opposed connected side panels interconnected to define a closed quadrilateral figure having open end portions. The invention contemplates an improved holding tab which is blanked out of the plane of the top panel in a manner so that the tab may be folded inwardly of the closed figure and extend between a pair of cans confined within the closed quadrilateral figure of the carrier. The arrangement is such that the tab is reversely folded so as to have a laterally offset portion which is adapted to engage the can at the tangent point thereof.

The arrangement is such that the lateral offsetting of the reversely folded end of the panel holding tab renders it possible to reduce the overall width of the blank to an optimum minimum whereby the width of the blank approaches $D(n-1)$ plus w_t where D equals the can diameter, n equals the number of cans in a can row, and w_t equals the width of the panel-holding tab.

This invention relates in general to a wrapper type can carrier and the like, and more specifically to a wrapper type can carrier having an improved panel holding tab constructed and arranged so as to result in a saving of material from which the carrier is formed without adversely affecting the overall strength and/or holding characteristic of the carrier.

Considerable effort has been made in the past to devise a carrier, usually formed of paperboard, cardboard and the like, to hold a plurality of chined end cans, such as beer cans, soda cans and other canned products, in a positive manner, while at the same time reducing to a minimum the amount of material or paperboard required to form the carrier. Because the use of such carriers constitutes an expense to the manufacturer of goods and products distributed in cans, constant efforts are being made to conceive a positive carrier in which the paper content can be reduced to minimize the cost thereof with the ultimate savings being passed to the consumer. Carriers of the type disclosed by U.S. Patent No. 3,032,185; Reissue Patent 25,111 and U.S. Patent No. 2,963,148 are typical of the heretofore known carrier constructions which have been conceived in an effort to achieve the end result hereinbefore set forth.

Accordingly, it is an object of this invention to provide an improved can carrier and blank constructed and arranged so as to enhance a still greater saving of material over the carriers heretofore known without adversely affecting the holding qualities and/or the can retaining characteristics thereof.

Another object is to provide a can carrier of the type disclosed in U.S. Patent No. 3,032,185; Reissue Patent

2

25,111; and, U.S. Patent No. 2,963,148 having an improved holding tab construction that will result in a further economy and/or saving of material from which the carrier is constructed.

5 Another object is to provide a wrapper type can carrier with an improved panel holding tab construction which is relatively simple and inexpensive to fabricate.

Still another object is to provide a can carrier specifically constructed to attain maximum strength through the minimum use of material.

10 Still another object of this invention is to provide a blank construction in which the overall width of the expanded blank for defining a closed quadrilateral figure for containing therein a plurality of cans disposed in can rows therein approaches $D(n-1)$ plus w_t where D equals the diameter of the cans, n equals the number of cans in a can row, and w_t equals the width of the panel retaining tab.

20 Another object of this invention is to provide in a can carrier, an improved tab construction which permits the free edge of the carrier to approach the point of tangency of the end most cans contained within the carrier.

25 Another object is to provide a wrapper type can carrier with a panel holding tab blanked out of the plane of a panel portion thereof so as to be folded inwardly of the carrier and reversely folded with respect to itself in outwardly offset relationship for engaging the chined end portion of a can at the point of tangency thereof and thereby permit the overall width of the wrapper blank to be minimized to result in savings in the amount of paperboard required to construct such a can wrapper.

30 Other objects, features, and advantages of this invention are attained by a wrapper type can carrier folded of a foldable blank of sheet material comprising a top panel, a bottom panel, and a pair of opposed connected side panels interconnected to define a closed quadrilateral figure having open end portions. Generally, such closed figures are sized to hold a plurality of rows of chined end cans disposed in side-by-side relationship wherein substantially one-half of the respective end most cans of the can rows extend beyond the open end portions of the closed figure. Means in the form of can retaining tabs are blanked out of at least of the top panel portion of the carrier to fold inwardly of the closed figure defined thereby for engaging the chined end of the cans to retain the same between the opposed panel portions thereof.

35 In accordance with this invention, a panel holding tab is blanked out of the plane of the top panel in a manner so that the tab may be folded inwardly of the closed figure and extend between a pair of end most cans to engage with one of them so that the adjacent panel may be held contiguous to the end of the cans. The arrangement is such that the tabs are spaced inwardly from the opposed end edge portions of the top panel and are foldable inwardly of the carrier about a foldline disposed in the plane of the top panel. Accordingly, each of the respective panel holding tabs are reversely folded along an intermediate foldline inwardly of the carrier so as to define a laterally offset reversely folded end portion, the free end of which is adapted to engage the chined portion of a can between the tangent points of the end cans. The reversely folded outwardly offset end portion of the panel holding tabs may fold about its respective intermediate foldlines to define either a J forming fold or a

t forming fold. The arrangement is such that the reversely folded laterally offset portion of the panel holding tab is adapted to engage the can along the center line thereof. Accordingly, it has been discovered that by laterally offsetting the reversely folded end of the panel holding tabs, the overall width of the blank from which the wrapper is formed can be reduced to a minimum wherein width of the blank approaches optimum minimum width of $D(n-1)$ plus w_t where D equals the can diameter, n equals the number of cans in a can row, and w_t equals width of the panel holding tab.

A feature of this invention resides in a can carrier which may be formed of a single sheet of foldable blank material in which the overall width of the blank is reduced to an optimum minimum of substantially $D(n-1) + w_t$, wherein D equals the diameter of the cans disposed in the can row, n equals the number of cans in the can row, and w_t equals substantially the width of the offset portion of the tab.

Another feature of this invention resides in a wrapper type can carrier having an improved panel holding tab which is provided with a reversely bent laterally offset portion specifically constructed and arranged so as to engage the chimed portion of a can at the point of tangency thereof to result in minimizing the overall width of the blank from which such carrier is formed.

Another feature of this invention resides in the provision of a wrapper type can carrier having an improved panel holding tab construction having a reversely folded laterally offset end portion defined as a J fold.

Another feature of this invention resides in the provision of a wrapper type can carrier having an improved panel holding tab with reversely folded laterally offset end portion defining a t shaped fold.

Another feature of this invention resides in a wrapper type can carrier formed of a single sheet of foldable blank material constructed with an improved panel holding tab which permits the overall width of the blank to be reduced to a minimum without adversely affecting the can holding qualities and/or characteristics of the carrier.

Other features and advantages will become more readily apparent when considered in view of the drawings in which:

FIGURE 1 illustrates a perspective view of the wrapper type carrier constructed in accordance with this invention for holding a plurality of can rows disposed in side-by-side relationship in which the can retaining tabs have not been shown to better illustrate improved portions of the carrier.

FIGURE 2 illustrates an expanded or plan view of the blank construction from which the can wrapper of FIG. 1 is formed.

FIGURE 3 is an enlarged fragmentary plan view of the carrier illustrating the improved tab construction in accordance with this invention.

FIGURE 4 is an enlarged vertical section view taken along line 4-4 on FIG. 3.

FIGURE 5 is a fragmentary plan view of a modified form of the invention.

FIGURE 6 is a fragmentary sectional view taken along line 6-6 on FIG. 5.

FIGURES 7 and 8 are comparison view of the improved tab construction of this invention (FIG. 8) as compared with a prior known construction (FIG. 7) to illustrate how the instant invention effects saving in material from which the carrier is formed.

Referring to the drawings, there is shown in FIG. 1 the improved can type wrapper 10 embodying the instant invention. The wrapper type carrier 10 of the type disclosed in FIG. 1 is particularly adapted for holding or containing therein a plurality of cans, as for example beer cans, soda cans, and various other cans in which goods are distributed.

Generally, such carriers 10 are constructed and arranged so as to contain therein six cans disposed in two rows of three cans each arranged in side-by-side rela-

tionship. However, it will be understood that the carrier need not be limited to six cans. Such carriers are generally formed from a single blank 11 of foldable sheet material, such as cardboard, paperboard, and the like; scored and folded to define a top panel 12, a bottom panel 13, and a pair of opposed side panels 14, 15 interconnected therebetween so as to define a closed quadrilateral figure having opened end portions. If desired, a suitable handle (not shown) may be formed integral therewith to facilitate carrying of the carrier. However, in the illustrated form of the invention, the means for facilitating the carrying of the carrier in the assembled and loaded position thereof comprises a pair of finger holes 16 formed in the top panel portion 12, as shown. The arrangement is such that the finger holes 16 are located so as to overlie the void defined between the adjacent cans in the respective can rows.

As best shown in FIGS. 1 and 2, the blank 11 from which the wrapper type can carrier 10 of this invention is formed comprises a single sheet of foldable material which is provided with a plurality of transversely extending fold-lines $F_1, F_2, F_3, F_4, F_5, F_6$ to define a top panel 12 disposed intermediate a pair of side forming panels 14, 15. Connected to the free edge of the respective side forming panels 14, 15 along foldlines F_3, F_4 is a panel section arranged to define a half portion or section 13A, 13B respectively of the bottom panel 13. Connected to the edge F_5, F_6 of the respective half bottom panels 13A, 13B along the foldline is an extended portion 17, 18 adapted to be reversely folded about foldlines F_7, F_8 in the assembled position of the carrier and secured together to define the closed quadrilateral figure as shown in FIG. 1. Accordingly, the free edge of the reverse folds of sections 17, 18 function to engage the bottom chimed end portion of the cans disposed on the adjacent half bottom panel section, as is evident in FIG. 1.

In the illustrated embodiment, the top panel 12 and each of the respective half bottom panels 13A, 13B are provided with can retaining tabs 19 blanked out of the respective planes thereof so as to be folded inwardly of the wrapper, as best seen in FIGS. 3 and 5 to engage with the adjacent chimed end of the can. The respective can retaining tabs 19 are folded inwardly about the respective foldlines F_{10} so as to underlie the panel from whence they are blanked. In this form of the invention it is to be noted that the can retaining tabs 19 are provided for retaining only the end most cans of the respective can rows, the middle or inner can being retained by the retained end cans of the respective can rows.

To provide positive retention of the cans by the can retaining tab 19, a panel retaining or holding means is provided for maintaining both the top and bottom panels contiguous to the top and bottom end walls of the cans disposed within the carrier. As hereinbefore described, the reversely folded end portions 17, 18 of the blank which are connected to the respective half bottom panels 13A, 13B function to retain the respective half bottom panels 13A, 13B contiguous to the bottom ends of the respective cans.

In accordance with this invention, an improved panel holding tab 20 is located in the top panel 12 of the wrapper. In accordance with this invention, the improved panel holding means 20 blanked out of the top panel of the wrapper are specifically constructed and arranged so as to permit a reduction in the overall width of the blank material from which the wrapper is formed to an absolute minimum so as to effect a maximum economy of saving of board, without adversely effecting the holding characteristics or strength of the carrier of the type to which the instant carrier relates. With the improved tab construction 20, as will be hereinafter described, the overall width W of the wrapper blank can be reduced to substantially $D(n-1) + w_t$ where D equals the diameter of the respective cans, n equals the number of cans in the can

row, and w_t equals the width of the improved panel retaining tab 20, as will be hereinafter described.

Referring more specifically to FIGS. 2, 3, and 4, it is to be noted that the improved holding tab 20 construction is blanked out of the top panel 12. As shown, the respective panel holding tabs 20 are disposed adjacent the outer longitudinal edge portion of the blank 11. The arrangement is such that the respective panel holding tabs 20 are adapted to be folded inwardly of the carrier along a foldline F₁₁ disposed in the plane of the top panel 12.

It is to be noted that the foldline F₁₁ about which the respective panel retaining tabs 20 is folded is disposed at an angle with respect to the longitudinal edge of the blank. While the foldline F₁₁ may be normal to the edge of the blank, in the illustrated embodiment the foldline F₁₁ of the tab is inclined to the edge of the board. Intermediate the length of the tab 20 there is provided an intermediate or second foldline F₁₂ which is inclined similarly to the illustrated foldline F₁₁ about which the retaining tab 20 is folded inwardly of the carton. Also, the free end 21 of the tab 20 is die cut on an angle so as in the operative position, as will be hereinafter described, it will engage the can chime at the tangent point. If desired, the one or both sides of the tab may be tapered so as to control the width of the free end 21 portion of the tab. Accordingly, in the operative position, as seen in FIGS. 3 and 4, the panel holding tab 20 in the assembled position of the wrapper is folded inwardly of the wrapper and reversely folded onto itself in laterally offset relationship so as to be disposed between the end cans C₁, C₂ of the respective can row adjacent the point of tangency therebetween.

Referring to FIG. 4, it is to be noted that the end portion 21 of the tab 20 is reversely folded so as to form a t-shaped fold whereby the reverse fold end portion 21 thereof is laterally offset as best seen in FIGS. 1, 3, and 8. Accordingly, the free, reversely folded, laterally offset edge 21 of the panel retaining tab is arranged to engage the tangent point between the end most cans C₁, C₂ of the can row, and thereby functions to positively retain the top panel 12 flush against the ends of the chimed can to insure positively retention of the can tabs 19 within the raised chimed end portion of the can and the top panel.

In a modified form of the invention, the reversely folded end portion 21 of the panel retaining tab 20 may be reversely folded to define a J fold as shown in FIGS. 5 and 6. Accordingly, it is to be noted that with the J fold retaining tab 20 of FIGS. 5 and 6, the free edge of the tab will engage the can C₁. When the panel retaining tab 20 is provided with a t-shaped fold, as disclosed in FIGS. 1, 3, and 4, the free edge of the reversely folded tab will engage can C₂.

With the construction described, the arrangement is such that the angular, laterally offset, reverse fold of the panel holding tabs 20 permit the overall width of the blank 11 from which the wrapper is formed to be reduced to a minimum. Referring to FIGS. 7 and 8, it will be noted that the overall width of the blank 11 from which the carrier is formed can be reduced on each side of the blank by a strip having a length coextensive with the length of the blank and a width equal to dimension X as evident in FIG. 7.

In the prior known construction of a blank of the type herein in question, as evidenced in FIG. 7, it is to be noted that the width of the blank had to be increased on each end by an added width equal to X in order to provide sufficient board between the free edge of the blank and the die cut which defines the outer edge of the panel holding tab in order to maintain the strength of the board adjacent the area from whence the holding tabs are blanked. Consequently, the overall width of the board of prior known constructions was required to account for this X dimension on both sides of the blank.

With the applicant's construction, as illustrated in FIG. 8, the improved holding tab 20, provided with a reversely

bent, laterally offset portion allows for the elimination or reduction in board of that amount equivalent to a strip having dimension X on both sides thereof. This is rendered possible, because with the instant construction panel retaining tab 20 may laterally offset in the folded position to engage the tangent point of the cans. Accordingly, the laterally offset reversely bent end portion of the respective panel holding tabs 20 allows the outermost point of the reverse bent portion of the tab to be substantially coincident with the outermost edge of the blank. Accordingly, by spacing the panel retaining flap 20 inwardly from the outer edges of the blank and by providing a laterally offset reversely bent fold, the arrangement is such that the free edge of the reversely bent laterally offset fold may still be located so as to engage the point of tangency of the can, and thereby enables the top panel to be retained contiguous to the chimed end portions of the can to affect positive retention of the cans therein.

With the construction described, it is to be noted that the overall width of the blank from which the wrapper is formed is effectively reduced, while at the same time permitting the panel holding tab 20 to be folded to engage the point of tangency between the adjacent end cans. Accordingly, savings of approximately 10 percent of board is effected thereby for any comparable carrier. In the industry to which the invention relates such a saving in board is considered to be substantial.

While the instant invention has been described with respect to several embodiments thereof, it will be readily appreciated and understood that variations and modifications of the invention may be made without departing from the spirit or scope thereof.

What is claimed is:

1. A can carrier comprising:
  - (a) opposed sides and connected top and bottom panels defining a closed quadrilateral figure having open end portions,
  - (b) means defining can retaining tab blanked out of one of said panels of said blank and folded inwardly thereof to engage the ends of said cans,
  - (c) and means for retaining said one panel against the ends of said cans to retain said can retainer tabs in operative position against the end of said cans,
  - (d) said latter means including a holding tab blanked out of the plane of said one panel adjacent the outer edge of said one panel,
  - (e) said holding tab being inwardly bent about a foldline disposed at an angle with respect to the outer edge of said one panel,
  - (f) said holding tab having formed intermediate the ends thereof an angularly disposed foldline relative to the side of said tab about which said holding tab is reversely folded so that the free end thereof is laterally offset with respect to the connected portion of the tab, the free edge of the lateral offset portion being coincident with the outer edge of the panel and engages the chime end of the can at the tangent point thereof.

2. A can carrier comprising:

- (a) a substantially rectangularly shaped blank of readily foldable material defining opposed sides, and connected top and bottom panels disposed in end-to-end relationship for enwrapping a row of chimed cans,
- (b) means defining can retaining tabs blanked out of the top panel of said carrier and folded inwardly thereof to engage the top of said cans,
- (c) and means for retaining said top panel against the top of said cans in the operative position of said carrier to retain said can retainer tabs in operative position against the top of said cans,
- (d) said latter means including a holding tab blanked out of the plane of said top panel adjacent the outer edge of said blank,
- (e) said holding tab being inwardly bent about a fold-

line disposed in the plane at an angle to the said outer edge which is other than normal of said top panel,

(f) said holding tab having formed intermediate the ends thereof an angularly disposed foldline relative to the side edge of said tab and substantially parallel to the angular foldline disposed in the plane of the top panel about which said holding tab is reversely bent so that the free end thereof is laterally and outwardly offset whereby the free end thereof engages the chime of one of the cans in said row at substantially the tangent point thereof,

(g) said outwardly offset reversely folded portion of said holding tab being coincident with the outer edge of said top panel whereby the width of the blank is reduced to an optimum minimum.

3. A can carrier comprising:

(a) a blank of readily foldable material defining opposed sides, and connected top and bottom panels for enwrapping a row of chimed cans,

(b) means defining can retaining tabs blanked out of the top panel of said blank and folded inwardly thereof to engage the top of said cans,

(c) and means for retaining said top panel against the top of said cans to retain said can retainer tabs in operative position between said top panel and the top ends of the cans,

(d) said latter means including a holding tab blanked out of the plane of said top panel adjacent the outer edges of said blank,

(e) said holding tab being inwardly bent about a foldline disposed in the plane of said blank at an inclined angle relative to the edge of said blank,

(f) said holding tab having formed intermediate the ends thereof transversely extending diagonal foldline about which said holding tab is reversely bent so that the free end thereof is adapted to engage the chime of one of the cans in said row whereby the respective foldlines of said tab enable said tab to conform to a circumferential portion of said can.

4. A wrapper type carrier blank adapted to enwrap a plurality of containers disposed in a row

(a) said blank comprising a sheet of rectangular folded sheet material defining opposed top and bottom panels adapted to be disposed contiguous to the tops and bottoms respectively of the chimed end cans disposed in side-by-side can rows, and

(b) opposed side panels interconnected between said top and bottom panels to define a closed quadrilateral figure having open sides whereby the overall width of said blank is equal to $D(n-1) + w_t$, and including

(c) can retaining tabs blanked out of the plane of said top and bottom panel for engaging the chime of the end most cans of a can row for retaining the same in position within said figure,

(d) and panel holding means connected to both said top and bottom panels to engage the chime of a container for holding said top and bottom panels parallel to and contiguous to the top and bottom of said cans to assure positive engagement of said can retainer tabs with the tops and bottoms of said container,

(e) said panel holding means of said top panel comprising a holding tab blanked out of the plane of said top panel,

(f) said holding tab being folded inwardly of said carrier about a foldline inclined to the edge of said top panel and reversely folded about a diagonal foldline disposed intermediate the ends of said tab and substantially parallel to said first-mentioned foldline so that the reversely folded end portions is laterally outwardly offset to permit the reversely folded free end of the holding tab to engage the chime of a can between the tangent point of said end most cans in said can rows.

5. A wrapper type carrier adapted to enwrap a plurality of cans disposed in side-by-side rows and comprising:

(a) an elongated blank having spaced transversely extending foldlines to define opposed top and bottom panels adapted to be disposed contiguous to the tops and bottoms respectively of the containers disposed in said row, and opposed side panels interconnected between said top and bottom panels to define a closed quadrilateral figure having open ends in the folded position of said blank,

(b) said side panels being adapted to be disposed contiguous to the outer side of the outermost row of cans,

(c) can retaining tabs blanked out of the plane of said top and bottom panel to engage the chime of the end most cans in said can rows for retaining the same in position within said figure,

(d) and panel holding means connected to both said top and bottom panels to engage the chime of one of said end most cans for retaining said top and bottom panels parallel and contiguous to the top and bottom of said cans to assure positive engagement of said can retainer tabs with the tops and bottoms of said container,

(e) said panel holding means of said top panel comprising a tab blanked out of the plane of said top panel,

(f) said holding tab being folded inwardly of said carrier about a foldline disposed in the plane of said top panel at an inclined angle to the edge of said top panel and reversely folded about a diagonal foldline disposed intermediate the ends of said holding tab and substantially parallel to said first-mentioned foldline,

(g) said holding tab having its reversely folded free end engaging the chime of a container between the tangent point of said end most cans of said can rows whereby the free edge of said reversely folded end is disposed coincident to said edge.

6. In a wrapper type can carrier having connected opposed wall panels to define a closed quadrilateral figure and having can retaining tabs blanked out of the plane of at least one of said wall panels whereby said can retaining tabs are folded inwardly of said carrier to engage the chime end of a can for retaining the same in position within said carrier, the improvement of a panel holding tab blanked out of the plane of said one wall panel to positively maintain said one panel contiguous to the end of the can, said panel holding tab being folded inwardly of the carrier about a foldline disposed in the plane of said one panel and inclined at an angle to the edge of said panel, and reversely folded about a second foldline extending transversely of said panel holding tab intermediate the ends of said holding tab to define a reversely folded end portion and a connected end portion, said reversely folded portion of said holding tab being laterally offset with respect to its connected end portion so that the free edge of said holding tab engages the chime of said can at the tangent point thereof and, said panel having an overall width equal to substantially $D(n-1)$ plus w_t where D equals the diameter of the can, n equals the number of cans in a can row, and w_t equals the width of said tab.

7. A wrapper type can carrier comprising a blank defining a closed quadrilateral figure having opposed wall panels and can retaining tabs blanked out of the plane of at least one of the wall panels of said blank whereby said can retaining tabs are folded inwardly of said carrier to engage the chime of a can for retaining the same in position within the closed figure, the improvement of a panel holding tab blanked out of the plane of said one wall panel to positively maintain said one panel contiguous to the end of the can, said panel holding tab being folded inwardly of the carrier about a foldline disposed in the plane of said one panel and extending at an angle other

than normal to the edge of said one panel, and reversely folded about a second disposed substantially parallel fold-line extending transversely of said panel holding tab intermediate the ends of said holding tab to define a reversely fold end portion and a connected end portion, said reversely bent portion of said panel holding tab being laterally offset with respect to its connected end portion so that the free edge of said panel holding tab engages the chime of said can at the tangent point thereof whereby the overall width of said blank equals $D(n-1) + w_t$ where D equals the can diameter, n equals the number of cans in can row adapted to be disposed in the carrier, and w_t equals the width of the free end of said holding tab.
